UNITED STATES PATENT OFFICE.

BENJAMIN S. CHURCH, OF NEW YORK, N. Y.

STEAM OR OTHER ENGINE.

SPECIFICATION forming part of Letters Patent No. 392,983, dated November 20, 1888.

Application filed August 24, 1887. Serial No. 217,724. (No model.)

To all whom it may concern:

Be it known that I, BENJAMIN S. CHURCH, of the city of New York, in the county and State of New York, have invented a new and 5 useful Improvement in Steam or other Engines, of which the following is a specification.

This invention relates to that class of engines in which the piston is actuated by a confined volume of a suitable elastic fluid which is alternately expanded and contracted by heating and cooling it.

Previous to my invention it had been proposed to alternately heat and cool the volume of confined fluid by driving it from one part of 15 a chamber, in which the fluid comes in contact with a hot tube or surface, to another part of such chamber, in which the fluid comes in 20 in contact with a cold tube or surface, a movable shield or partition being employed within the said chamber for covering either the hot or cold tube or surface and driving the fluid from one part of the chamber into the other—as, for instance, in the patents to McTighe, No. 321,739, July 7, 1885, and Willcox, No. 9,871, July 19, 1853. It had also 25 been proposed to revolve these chambers for the purpose of causing the heating and cooling agents to act alternately upon the same part of the chamber, as in the patent to Hidden and Reeves, No. 21,133, August 10, 1858.

The object of my invention is to effect the alternate heating and cooling of the confined volume of fluid without the employment of movable parts within the chambers which are 35 exposed to the pressure of the fluid and without moving the chambers themselves, which would necessitate the use of moving joints exposed to the pressure of the fluid, thereby avoiding leakage and reducing the resistance 40 of the parts within the engine to a minimum, whereby the engine is simplified and greater economy in the consumption of fuel is secured.

In the accompanying drawings, consisting of 45 two sheets, Figure 1 is a longitudinal sectional elevation of my improved engine. Fig. 2 is a horizontal section thereof, partly shown in plan view. Fig. 3 is a vertical cross-section in line $x\ x$, Fig. 2. Fig. 4 is a vertical cross-section in line $y\ y$, Fig. 2. Fig. 5 is a horizontal sec-

tion in line $x\ x$, Fig. 3. Fig. 6 is a fragmentary side elevation of the engine. Fig. 7 is an enlarged sectional elevation of the passages connecting the boiler with the heating and cooling chambers. Fig. 8 is a similar view of the equalizing-valves.

Like letters of reference refer to like parts in the several figures.

The principle upon which my invention is based consists in the alternate heating and cooling of confined or isolated volumes of an 50 elastic fluid, whereby unequal pressures are produced on opposite sides of the piston which traverses the cylinder of the engine.

A high initial pressure of air or any other elastic fluid may be used as the medium of 55 power.

For illustration, I will describe my invention with reference to the employment of steam as the expanding medium and hot air or the products of combustion as the heating medium and cold air as the cooling medium. This alternate heating and cooling is effected in my invention in chambers communicating with the cylinder, the piston separating the two volumes of steam in the chambers and 70 cylinder on opposite sides of the piston. The heating and cooling of the steam is effected in these chambers by circulating currents of hot and cold air, which are alternately directed 75 through each chamber and whereby the steam is alternately expanded and contracted. While the steam is being expanded by a hot current on one side of the piston it is contracted to about the initial pressure and temperature by a cold current on the opposite 80 side of the piston, causing unequal pressures on opposite sides of the piston, whereby the piston is actuated.

A represents the cylinder, provided with 85 ports $a\ a'$.

B represents the piston, secured to a rod, b , which transmits the power to the shaft C by a cross-head, c , and pitman c' .

D D' represent the fixed heating and cooling chambers, communicating, respectively, 90 with the cylinder by the ports $a\ a'$. These chambers are provided, respectively, with upright tubes or flues $d\ d'$, around which the

steam-space is formed in each chamber, while the hot and cold air currents pass through the tubes.

E E' represent the connected exit-passages 5 through which the air-currents escape from the upper ends of the tubes d d', and e e' represent the inlet-passages for said currents leading to the lower ends of said tubes.

F represents a small upright steam-boiler 10 arranged between the chambers D D', and having its steam-space connected with the upper ends of the chambers by a passage, f, valve-chamber f', and pipes f² f³, as represented in Figs. 1, 3, and 7. The valve-chamber 15 f' is provided with partitions g g' on opposite sides of the passage f, in which partitions are seated check-valves G G', which close toward the steam-boiler and open toward the chambers d d', so that these valves 20 open when the pressure in the boiler exceeds the pressure in the chambers and permit the steam to pass from the boiler into the chambers or chamber in which the pressure is below the boiler-pressure, while the valves close when 25 the pressure in the chambers exceeds the boiler-pressure.

H represents the furnace or fire-box, arranged below the boiler. h represents the grate, and h' a sliding damper arranged in the 30 upper part of the fire-box, below the bottom of the boiler.

i i' represent ports connecting the fire-box H respectively with the inlet-passages e e' of the chambers D D', and I I' represent valves 35 or dampers by which the ports i i' are alternately opened and closed. The dampers I I' are connected by rods j j' with a rock-arm, J, which is actuated from the engine-shaft C by an eccentric, K, and rod l. The latter passes 40 through a lug, l', on the rock-arm J, and is provided with stops l² l³, which come alternately in contact with the lug l' and actuate the rock-arm J intermittently. Any other suitable mechanism for opening and closing 45 the dampers I I' may be employed, if desired.

L represents a fan-blower or other air-propelling apparatus, having its blast-pipe l connected with two channels or passages, l' l'', which are arranged on opposite sides of the 50 fire-box H and communicate with the inlet-passages e e' of the chambers D D', so that the blast entering either of the channels l' l'' passes upwardly therefrom through the respective inlet-passages e e' and the tubes d d' of the chamber communicating therewith. The 55 dampers I I' close the channels l' l'' when they open the ports i i', and vice versa, as represented in Fig. 1. The fan-blower L is preferably actuated by a belt, m, from a pulley, M, 60 on the engine-shaft.

The valves or dampers whereby the hot and cold currents are alternately directed through the fixed heating and cooling chambers need not be fitted any tighter than ordinary stove-dampers, and consequently require but little 65 power for their operation. The heating and

cooling chambers being fixed and connected with the passages for the fluid by fixed joints, the wear, friction, and leakage attending the use of movable joints are avoided.

The steam-spaces of the chambers D D' communicate with each other by pipes n n' and an intermediate valve-chamber, N, in which are arranged two valves, o o', which close inwardly or toward each other. This valve 75 mechanism is arranged between the cylinder A and the steam-boiler, as represented in Figs. 2 and 3.

p represents an actuating finger or arm which is arranged in the valve-chamber N, 80 and which engages against the stem of either valve, so as to open the same against the pressure in the respective chamber toward which the valve opens, while the valve seats itself when released by the pressure in the chamber. 85 The arm or finger p is secured to a vertical rock-shaft, P, which extends downwardly from the valve-chamber, and is provided at its lower end with an arm, p'.

q represents a finger or nose secured to the 90 rod j, which connects the dampers I I', and projecting rearwardly therefrom, so as to come in contact with the arm p', as represented in Fig. 5. The nose q is so arranged on the rod j that it moves the arm p and opens one of 95 the valves o o' just before the piston reaches the end of its stroke.

r r' represent vent-cocks applied to the steam-spaces of the chambers D D'.

The operation of this engine is as follows: 100 Steam is generated in the boiler F by the fire on the grate h, the damper h' being open, so as to give free access of the heat to the boiler. When the steam-pressure in the boiler reaches the desired initial pressure—for instance, sixty 105 pounds to the square inch—the valves G G', which are properly weighted by springs, open and permit the steam to pass from the boiler to the chambers D D' and the cylinder A on both sides of the piston. The air contained in 110 the steam-spaces of the chambers D D' and cylinder A is expelled by the steam through the vent-cocks r r'. When all of the air has been expelled, these cocks are closed. The steam-spaces in the chambers D D' and cylinder A are now filled with saturated steam of 115 the desired initial pressure. When the parts are in the position represented in Figs. 1 and 2, the hot products of combustion pass from the fire-chamber H through the passage i, inlet-passage e, tubes d, and exit-passage E, thereby heating the steam in the chamber D and in that part of the cylinder A which communicates with the port a. The damper I' being closed, cold air can pass through the tubes d' 120 of the chamber D'. In this manner the steam is heated and expanded on one side of the piston, creating an over pressure which propels the piston in the direction of the arrow, Fig. 2. When the piston has nearly reached the end of 125 the stroke, the valve o is opened by the arm p, thereby placing the expanded steam in the

chamber D in communication with the steam of initial pressure in the chamber D'. The valve o' is raised from its seat by the over-pressure and the pressure becomes equalized, 5 and in the chambers D D' and the cylinder A on both sides of the piston, the pressure and heat falling in the chamber D and rising in the chamber D'. The dampers I I' are shifted at the same time, the damper I' being opened 10 and the damper I closed, so that the hot current now passes through the tubes d' of the chamber D', while the cold current passes through the tubes d of the chamber D. This causes a reduction of the pressure before the 15 piston and an increase of the pressure behind the piston, whereby the piston is caused to move through the cylinder in an opposite direction. When the piston has nearly reached the end of its return-stroke, the valve o' is 20 opened, thereby again equalizing the pressure on both sides of the piston. The dampers I I' are at the same time shifted to the position represented in Fig. 1. In this manner hot and cold currents are successively directed 25 through each chamber D D', thereby causing successive expansions and contractions of the same confined volumes of steam, loss of steam from leakage, and also the pressure of these volumes of steam is prevented from falling 30 below the initial pressure by steam supplied to the chambers D D' from the boiler F through the pipes f f' f'' and valves G G'. When the engine is in normal operation, but little fresh steam is required to be supplied from the 35 boiler to the chambers D D', and the damper h' is nearly closed, so as to direct the bulk of heat from the fire-box H to the chambers D D'. The cold blast driven through one chamber by the fan-blower L and escaping from 40 either of the connected pipes E E' causes by induction a strong draft of hot gases through the other chamber. I prefer to employ a blower for this purpose on account of its uniform action; but it is obvious that a strong 45 chimney-draft, causing the flow of hot gases through one chamber, will by induction cause a corresponding flow of cold air through the other chamber, in which case the blower may be omitted. By equalizing the pressure on 50 both sides of the piston, as described, the relative pressures on both sides of the piston are to a certain extent regulated, the heat and pressure of the volume of steam to be next expanded is increased before the hot blast is applied, and the heat and pressure in the volume 55 to be cooled is reduced just before the cold blast is applied, thereby effecting an important economy in fuel.

For the purpose of preventing loss of heat 60 by radiation, the parts in which the steam is contained are preferably protected by non-conducting material. The piston is also provided with a non-conducting lining to prevent radiation through the piston from the high-pressure to the low-pressure volume of steam. 65

The cubical contents of each chamber are

preferably about equal to the cubical contents of the cylinder.

The cold blast should be so regulated that it does not chill the steam to the point of condensation. 70

In the engine herein described all that is required of the boiler is that it shall furnish the initial charge of steam to the cylinders and chambers and make good the loss of steam by 75 leakage and partial condensation, which is effected automatically, as described, by means of the valves O O' and the arms p p'. The boiler capacity to meet these requirements being small compared with the amount of heat 80 generated in the fire-box, the risk from explosion as compared with that risk in boilers for ordinary engines is proportionally diminished.

I claim as my invention— 85

1. The combination, with the cylinder and piston, of fixed heating and cooling chambers communicating with the cylinder and provided with passages for heating and cooling media, and valves or dampers whereby the 90 heating and cooling media are alternately directed through said passages, substantially as set forth.

2. The combination, with the cylinder and piston, of heating and cooling chambers communicating with both ends of the cylinder, a furnace, and dampers whereby the heated 95 gases are alternately directed from said furnace through either chamber, substantially as set forth. 100

3. The combination, with the cylinder and piston, of heating and cooling chambers communicating with the cylinder, a furnace, an air-propelling device, and dampers whereby the hot and cold currents are alternately directed 105 through each chamber, substantially as set forth.

4. The combination, with the cylinder and piston, of fixed heating and cooling chambers communicating with the cylinder and provided with passages for heating and cooling media, valves or dampers whereby the heating and cooling media are alternately directed through said passages, a steam-boiler, and automatic valves whereby steam is admitted to 115 the fluid-spaces of the engine from said boiler, substantially as set forth.

5. The combination, with the cylinder and piston, of a valve-chamber communicating with both ends of the cylinder, automatic 120 valves seated in said chamber and held in their seats by the pressure in the respective ends of the cylinder, and actuating mechanism whereby one of the valves is raised from its seat to equalize the pressure at the end of each stroke, 125 substantially as set forth.

6. The combination, with the cylinder and piston, of the heating and cooling chambers D D', connected exit-passages E E', inlet-passages e e', furnace H, and dampers I I', whereby 130 the hot gases are alternately directed into the passages e e', substantially as set forth.

7. The combination, with the cylinder and piston, of the heating and cooling chambers D D', inlet-passages e e', furnaces H, dampers I I', channels l l', and a blower, L, having its discharge-pipe connected with said channels, substantially as set forth.

8. The combination, with the cylinder and piston, of the heating and cooling chambers D D', boiler F, furnace H, passages e e', and a

damper, h', interposed between the furnace and the boiler, substantially as set forth.

Witness my hand this 10th day of August, 1887.
